CLAIM

The ornamental design for a dual bag with an inner bag with pattern and first pigment and an outer bag with pattern and second pigment, as shown and described.

DESCRIPTION

FIG. 1 is a front perspective view of a bag that includes an inner bag with a pattern and first pigment and an outer bag with pattern and a second pigment, where the second pigment is different from the first pigment;

FIG. 2 is a front view of the bag of FIG. 1, the back view being the same as the front view;

FIG. 3 is an exploded view of the bag of FIG. 1 showing the inner bag with pattern and first pigment, and the outer bag with pattern and the second pigment;

FIG. 4 is a detail view of a portion, designated by broken line box 4a of FIG. 3, of the inner bag with pattern and first pigment;

FIG. 5 is a detail view of a portion, designated by broken line box 5 of FIG. 3, of the outer bag with pattern and second pigment;

FIG. 6 is a cross-section view taken along line 6-6 of the portion shown in FIG. 4;

FIG. 7 is a cross-section view taken along line 7-7 of the portion shown in FIG. 5;

FIG. 8 indicates a stretched configuration of the portion shown in FIG. 4;

FIG. 9 indicates a stretched configuration of the portion shown in FIG. 5; and,

FIG. 10 indicates a stretched configuration of a portion, designated by broken line box 10 in FIGS. 1 and 2, of the outer bag with pattern and first pigment over the inner bag with pattern and second pigment.

The broken lines in the drawings illustrate portions of the dual bag that form no part of the claimed design. Where a broken line box is indicated, material inside the box is part of the claimed design. The bracket showing broken away portions illustrate the bag has no specific length. No particular pigment color is claimed for either the inner bag or the outer bag, and in an embodiment, one of the pigments may be darker than the other pigment.
